UNITED STATES PATENT OFFICE.

KAREL FREDERIK HENNEMAN, OF THE HAGUE, NETHERLANDS, ASSIGNOR OF ONE-HALF TO PIETER KERKHOVEN, OF THE HAGUE, NETHERLANDS.

SWITCH FOR ELECTRIC WATER-HEATING APPARATUS.

Application filed November 6, 1923, Serial No. 673,211, and in the Netherlands November 7, 1922.

The invention relates to a switch for electric waterheating apparatus, which is to be arranged in the conduit pipe and which switch closes by means of the water pressure in an electric water-heating circuit when a dry-cock is opened.

The object of the invention is the provision of hot water in a simple and quick manner and at any desired moment by means of electricity, at the same time reducing the consumption of electric current to a minimum and preventing the fusing of the heating-wires.

The invention consists in the provision of a switch for electric water heating apparatus to be arranged in the water conduit and which, by means of the water pressure, switches in an electric water-heating circuit, when a dry cock is opened and which switch comprises a cylinder having a pistonlike pressing member provided with one or more canal-shaped perforations, said pressing member being pressed by means of levers and of counter acting means to the position wherein the water supply over the by-pass is closed, said pressing member having also a piston rod movable over a certain distance in an axial direction, which piston rod is provided with a valvelike ledge, which, when the piston is moved against the action of counter acting means under the influence of the water pressure, closes the perforations, whereas when the movement of the piston continues the piston rod is pushed forward and switches on the electric current by means of the levers.

As, when opening the dry-cock the heating circuit is closed, hot water can immediately be supplied and as the circuit is also immediately automatically broken when the dry-cock is closed it is impossible to consume more current than is necessary. A further advantage is that always fresh water is supplied, because it is not forced to first pass a collecting tank.

An embodiment of the invention is shown in the accompanying drawings:

Fig. 1 shows a cross-section of a switch;

Fig. 2 shows a front elevation of the switch according to Fig. 1;

Fig. 3 is a switching device for switching in two or more heating apparatus, and

Fig. 4 is a switching device wherein the switching in is effected by means of a relay.

The switch is mounted on a marble plate

1. By means of the connecting member 36 the switch is connected to the water conduit and by means of the connecting member 37 to that part of the conduit which leads to a heating apparatus. These connecting members 36 and 37 form part of a cylinder 35, which at 9 and 10 is fixed on the plate 1 and through which the water passes when opening the dry-cock. A pistonlike pressing member 38 is arranged in the cylinder, which is located against the wall of the cylinder by means of piston rings 39. Furthermore the piston 38 is provided with some canal-like perforations 40, the purpose of which is described hereafter. At one end 60 a small shaft 41 extends through the cylinder and at the other end a small shaft 42. One end of the shaft 41 projecting from the cylinder carries a lever 43, on which is arranged a controlling weight 44. Inside the cylinder this shaft 41 is associated with the piston 38 by means of levers 45 and 46. Furthermore a valvelike rod 47 extends through the piston, to which is connected a rod 48, which in turn is hingedly connected 70 to the lever 49 fixedly coupled to the shaft 42. At one of the ends of the shaft 42 projecting from the cylinder 35 is a lever 50, which is coupled to one end of a rod 13. The cylinder 35 further possesses a by-pass 85 51, which at 52 and 54 is associated with the inner portion of the cylinder 35. At 52 a regulating valve 55 is arranged.

That end of the rod 13 which is not connected to the lever 50 is supported in a slot 90 15 of a disc-shaped member 14. This member 14 is fixedly mounted on a shaft 16 which rests in bearing-pedestals 17. On the member 14 there is also provided a ledge 18 formed as a cam. In the opened position of the switch this cam lies against a disc 19 of insulating material, which is carried by one of the arms of a double-armed lever 20. The end of the other arm of said double armed lever carries a contact 21 which cooperates with the second contact 22 fixedly mounted on the plate. Each of these contacts is connected to the terminal 23, 24, respectively. The arm 20 is mounted on a shaft 25, which lies in bearings 26. By 105 means of a drawspring 27 the contacts 21 and 22 may firmly be pressed together. A suitable conduit, which is coupled to the connecting member 37, serves to connect the cylinder 35 through which the water passes 110

to the heating apparatus. If now the dry-cock is opened, the pressure exerted by the water will push the piston 38 forward, while 52 allows to pass a quantity of water, 5 which previously has been regulated by the valve 55. This valve 55 is adjusted in accordance with the capacity of the apparatus so as to preclude the possibility of the 10 passage through the apparatus of a volume of water in excess of that which can be heated to the required temperature.

During the first movement the piston 38 will engage the valvelike ledge of the piston rod 47, which closes the perforations in the 15 piston and by a further movement of the piston, the piston rod is also moved in a forward direction and switches on the electric current by means of levers. Owing to the forward movement of the piston 38 the controlling weight 44 has reached the position indicated by the dotted lines, whereas 20 also lever 50 has come to the position shown by the dotted line. In this manner the rod 13 has been moved upward in the slot 15 and has positioned itself against the upper-side of this slot and pressed away the disc-shaped member 14. The shaft 16 has also 25 made a rotating movement and has removed the cam 18 from the disc 19 of the double-armed lever 20. By the action of the spring 27 and by the weight of the arm 20 the contact 21 is brought to the contact 22, so that the water heating circuit is switched in. If subsequently the dry-cock is closed the 30 water in the cylinder will stand still and no further action will be exerted on the piston 38. By means of the weight 44 the piston 38 will be moved back, will push against the nut 56¹ of the rod 47 and drag 35 away the rod 50. The rod 13 is moved downward and rotates the disc-shaped member 14 and shaft 16, for which purpose an additional weight 34 has been arranged 40 on shaft 16 thereby causing the lever 20 to move upward and to break the heating circuit. By means of the canals 40 which pass through the piston 38 the pressure at both 45 sides of the piston is compensated.

More dry-cocks may supply hot water according to the capacity of the heating apparatus.

Further the temperature of the water may be regulated in a simple manner viz by opening the dry-cock more or less.

A good regulation may also be obtained by using a plurality of heating apparatus (having switching devices as shown at Figs. 3 and 4). The switch itself is then so adjusted that for example when opening one 60 dry-cock the lever 50 by means of the piston 38 is rotated so far that one of the heating apparatus is first switched in. By opening two or more cocks the pressure exerted on the piston may then be made so heavy that 65 it is moved further forward, turns the arm-

50 to a greater extent and thereby switches in a second heating apparatus. This may be obtained in a simple manner by making the rod 13 longer and having it operate a second disc 14 (vide Fig. 3). The switching 70 off of the circuits for the various heating apparatus is then also successively effected.

Furthermore rod 13 may also be connected to a switch-arm 56 of a contact bridge 57. Each of the contacts *a*, *b*, *c* etc. of the latter 75 is associated with a relay, which after having been energized, switches in a switch for a heating apparatus (vide Fig. 4). When opening one dry-cock for example the arm 56 will be turned to the contact *a* by means 80 of the rod 13, the relay of the first apparatus will be energized and thereby the switch for the supply-current of this apparatus will be switched in. When subsequently opening a second cock for example the switch-arm will also be turned to contact *b*, whereby the second apparatus is switched in, and so forth.

It is clear that the switch may be so adjusted, that for example the first contact is 90 not passed before a determined number of cocks has first been opened.

In order to prevent the burning of the contacts the device may further be so constructed that the arm 56 first energizes a 95 low-current relay. The armature of this relay then closes a circuit for a power current relay, which after having been energized closes the heating circuit.

Having now described my invention, what 100 I claim is:

1. A switch device of the character described particularly for electric water heating apparatus, comprising a cylinder, a piston like member, having at least one perforation extending therethrough, a by-pass communicating with the cylinder spaces at both sides of the piston and means immediately accessible for adjusting this by-pass, means for automatically moving the piston 105 to close the by-pass at one end, a piston rod movable relatively to the piston, a valve member on the said piston rod for closing the said perforation in the piston and a switch operated by the movement of the piston 110 to switch on and off the electric current.

2. A switch device of the character described particularly for electric heating apparatus, comprising a cylinder, a piston like member, having at least one perforation extending therethrough, a by-pass communicating with both sides of the piston, an energy storing device and lever connecting means for automatically moving the piston 115 to close the by-pass at one end, a piston rod movable relatively to the piston, a valve member consisting of an annular ledge on the said piston rod for engaging the piston 120 and closing the said perforation in the piston when the latter is moved against the ac- 125

tion of the said energy storing device by water-pressure, and a switch operated by the movement of the piston to switch on and off the electric current.

5 3. A switch device of the character described particularly for electric heating apparatus, comprising a cylinder, a piston like member, having at least one perforation extending therethrough, a by-pass communicating with both sides of the piston, a counter-weight and lever connecting means for automatically moving the piston to close the by-pass at one end, a piston rod movable relatively to the piston, a valve member 10 consisting of an annular ledge on the said piston rod for engaging the piston and closing the said perforation in the piston when the latter is moved against the action of the counter-weight by water-pressure, and a 15 switch operated by the movement of the piston to switch on and off the electric current.

4. A switch device of the character described particularly for electric water-heating apparatus, comprising a cylinder, a piston like member having at least one perforation 25 extending therethrough, a by-pass communicating with both sides of the piston, means for automatically moving the piston to close the by-pass at one end, a piston rod 30 movable relatively to the piston, a valve member on the said piston rod for closing the said perforation in the piston, and a switch comprising fixed and movable contact members, a swinging member carrying 35 the movable contact members, a rotary cam device for operating the swinging member and link and lever connections between the piston and said cam device for operating the switch by the movement of the piston 40 to switch on and off the electric current.

In testimony whereof I affix my signature.

KAREL FREDERIK HENNEMAN.
